MACHINE FOR INSERTING FASTENINGS.

1,115,504.

Specification of Letters Patent.

Patented Nov. 3, 1914.

Application filed December 1, 1911. Serial No. 663,385.

To all whom it may concern:

Be it known that I, LOUIS A. CASGRAIN, a citizen of the United States, residing at Beverly, in the county of Essex and State of Massachusetts, have invented certain Improvements in Machines for Inserting Fastenings, of which the following description, in connection with the accompanying drawings, is a specification, like reference characters on the drawings indicating like parts in the several figures.

This invention relates to machines for inserting fastenings and is particularly useful when embodied in a fastening inserting machine of the type herein shown in which the fastening is formed from a continuous strip of fastening material by first inserting the end of the strip and then severing a measured length. Excepting those novel features which constitute the present invention, the illustrated machine is substantially like that disclosed in United States Letters Patent No. 1,053,479, granted Feb. 18, 1913, to L. A. Casgrain, for improvements in machines for inserting fastenings. To the said patent reference may be had for a complete description of the parts of said machine herein shown.

As more fully set forth in the aforementioned Letters Patent, the fastening inserting mechanism of the machine herein shown comprises a pair of normally reciprocating cutters which, when the machine is operating to insert fastenings, grip an interposed fastening strip, insert the end of the strip into the work, and then sever the strip at the point where it has been gripped. The end of the strip which is to be inserted into the work obviously extends below the cutters and unless provision is made to guide it it may fail to enter the work at the desired point, and when the machine is provided with an awl which makes an awl hole to receive the fastening it may either fail to enter the awl hole at all or may so enter said hole as to enlarge it and spoil the appearance of the work. When the cutters are equally sharp and are properly adjusted and when the strip is of uniform character throughout, little difficulty is experienced in inserting the end of the strip at the desired point. If, however, one of the cutters is sharper than the other so that when they are moved toward each other to grip the fastening strip the strip is moved

to one side of a point midway between the cutters, owing to the fact that one of them cuts into the strip more easily than the other one does, a tendency is given to the projecting end of the strip to tip out of the line in which it should move during the inserting operation. Again, if through carelessness the cutters have been so adjusted that their edges are not directly opposed, or if the bearings have become worn so that one tends to lag behind the other, a tendency is also given to the projecting end of the strip to tip out of the line of drive. Moreover, the original curvature of the strip due to coiling, usually persists to some extent and gives the end of the strip a tendency to deviate from the line of drive. Owing to the foregoing and other contingencies which affect the quality of the work by causing a tendency in the projecting end of the strip to move out of the proper line of drive, the machine as hitherto constructed has required especial attention upon the part of the operator to keep it in adjustment and has required especial nicety of adjustment to produce the best work.

An important object of the present invention, therefore, is to improve the machine in the foregoing respects by making it less sensitive to slight variations in the positions or conditions of the cutters and to deviations of the fastening strip owing to the persistence of its original curvature.

A particular object of the invention is to provide guiding means which will operate to engage the end of the strip to be inserted and guide it during the inserting operation.

Another object of the invention is to provide improved means for controlling the movements of the cutters which will insure uniform action of the cutters at the critical points in their sequence of operations, even though the bearings of the cutters and the connections between the cutters and their actuating means become more or less worn.

In the accompanying drawing,—Figure 1 is a front elevation of the upper portion of a machine embodying this invention in its preferred form; Fig. 2 is a perspective detail, partly in section, illustrating the fastening inserting mechanism with the parts in the positions which they assume just before the fastening strip is gripped by the cutters; Fig. 3 is a perspec-

tive view similar to Fig. 2, showing the parts in the positions which they assume just after the fastening strip has been gripped by the cutters; Fig. 4 is a perspective view similar to Figs. 2 and 3 showing the positions of the parts at the time the fastening is being severed from the strip by the cutters; Fig. 5 is a transverse section on the line 5—5 of Fig. 4; Fig. 6 is a detail plan showing the manner in which the strip is engaged by the guiding means, and Fig. 7 is a perspective detail of one of the cutters.

As above suggested, the machine in which the invention is shown as embodied is substantially that disclosed in said Letters Patent above identified, and comprises a standard 10 which supports a head 12 in which the principal operative parts of the machine are carried. The main driving shaft 20 14 is normally connected with a source of power when the machine is in use, and the interruption of the insertion of fastenings is effected without stopping said shaft by moving the fastening strip out of operative relation to the cutters by which it is gripped, inserted and severed. These cutters, which are indicated at 46 and 48 in Fig. 1, are mounted in carriers 42 and 44 which are pivoted at their outer ends at 50 and 52 to oppositely extending arms of a T-shaped reciprocating head 40 arranged to reciprocate in a swinging frame 24 which swings about the axis of the shaft 14.

The fork members 72 and 74 of a forked slide 66 are pivotally connected at 76 and 78 to the respective cutter carriers 42 and 44. The slide 66 has connections with a cam upon the rear face of the cam disk 34, said cam being not herein shown but being fully described in the Letters Patent above referred to. The timing of this cam is so related to the reciprocating movement of the head 40 that at each rotation of the main shaft the slide 66 is caused first to move relatively to the cutter carrier head 40 at the beginning of the downward movement of the head to cause the cutters to move simultaneously toward a line through their pivots and thus to close upon and grip an interposed strip of fastening material, then to move with the head whereby it holds the cutters positively from movement in either direction relatively to the head while they are being carried downward to force the end of the strip into the work, and then to move relatively to the head to cause the cutters to sever the strip after the end has been inserted to the desired extent, and finally to move relatively to the head, as the head again rises, to cause the cutters to separate to permit them to pass freely over the strip in their upward movement.

The frame 24 is swung laterally to effect the work feeding operation through connections with a cam groove 32 in the cam disk

34, comprising a lever 26, pivoted at 28 upon the machine head and carrying at its upper end a cam roll which enters the cam groove 32, and a link 36 pivotally connected at one end to the frame 24 and pivotally connected at its other end to a clamp 38 upon the curved lower arm of the lever 26, all as more fully described in the Letters Patent above referred to. The feeding of the work is effected principally, as in the machine of the Letters Patent, by means of an awl, the work feed being assisted, however, by a feeding and guiding plate which engages the projecting end of a partially inserted fastening. After the last fastening has been partially inserted and the awl has been moved out of operative relation to the cutters, as more fully described in the Letters Patent, the feeding of the work into position to bring the partially inserted fastening beneath the feeding and guiding plate is effected entirely by the action of said plate. It will thus be seen that, although for the most of the successive operations of the machine the feeding function of the feeding and guiding plate is not essential to the successful operation of the machine, since the principal burden of the feeding operation is placed upon the awl, it is important that this function be retained in order to insure the completion of the insertion of the last fastening of a series.

The fastening strip, as in the machine of the Letters Patent, passes through a retainer 80 by which its vertical relation to the cutters is controlled and through a presenter 117 by which its horizontal relation to the cutters is controlled, the presenter 117 being provided with a series of guiding grooves, as in the machine of the Letters Patent, so that a plurality of strips may be kept in readiness to be presented to the inserting mechanism.

The feeding and guiding plate is indicated at 412, but it will be noted that its structure is somewhat different from that of the correspondingly numbered element of the machine of the Letters Patent, this modification of the structure of this element constituting one of the principal features of the present invention. In the machine as hitherto constructed, the feed plate 412 has been provided with an opening which surrounded the end of the fastening strip, but it has not been practicable to make this opening of such a size that its sides would engage the sides of the strip and serve as effective guiding means therefor. This has been partly due to the fact that the opening in the feed plate 412 contains the projecting end of the partially inserted fastening at the time the work is being fed, and in order to permit the feeding of the work along a curved path the opening must be large enough to permit some movement of

the fastening transverse to the path of movement of the feed plate. The necessity for enlarging the opening to permit such lateral movement is accentuated when the 5 feeding of the work is effected by a two-point engagement of the machine with the work, as when the work is being fed both by the engagement of the feed plate with a projecting slug and the engagement of the 10 awl 162 with the work.

To provide effective means for guiding the fastening during the inserting operation, and at the same time to retain so much of the feeding function of the feed plate as 15 is necessary to complete the operation of the machine, is one of the principal objects of the present invention. To this end the construction of the feed plate has been so modified that it constitutes an element of a 20 new strip guiding means arranged to guide the portion of the strip which is below the point at which the strip is gripped by the cutters. Coöoperating with this modified feed plate is another element which moves 25 into and out of engagement with the strip and serves, therefore, to force the strip tightly into the guiding groove in the feed plate and to maintain it in said groove during 30 the greater part of the fastening inserting operation and then to release the strip so that there will be no interference with the work feeding operation, particularly when feeding around a curve.

The element which coöperates with the 35 modified feed plate 412 is contained in a recess 450 formed in a forwardly projecting enlargement of the front plate 451 of the reciprocating cutter carrier head 40 and comprises a strip engaging member or dog 40 452 provided, in the illustrated construction, with a V-shaped notch 454 which is adapted to embrace two sides of the strip herein shown, said strip being diamond-shaped in section. The other two sides of 45 the strip are received in a corresponding V-shaped notch 455 in the feed plate 412. The strip engaging member 452 is so shaped in that portion which contains the notch 454 that it will enter part way into the V in the 50 plate 412, see particularly Fig. 6 of the drawings. The member 452 is slidingly mounted in a pivoted controlling device 456 by which its movements toward and from the fastening strip are controlled, the member 55 452 being provided with a stem 458 which is received in a substantially vertical bore in the controlling device 456. The controlling device 456 is pivoted to swing in the recess 450 in the plate 451 by means of a 60 pivot pin 460 which passes through the controlling device 456 and also cuts across the bore in which the stem 458 is received, this stem being recessed, as shown at 462, to provide for vertical movement relative to the 65 controlling device, the amount of vertical

movement being limited by the engagement of the ends of the recess 462 with the pivot pin 460. The controlling device 456 is normally pressed toward the cutters and toward the fastening strip by a spring 464 received 70 in a socket in the front wall of the recess 450, said spring having an end 466 which is received in a transverse slot 468 in the pivot pin 460 whereby it keeps the pivot pin from sliding out of its bearings. The controlling 75 device 456 is forked at its lower end and each of the fork members is adapted to co-operate with the adjacent cutter in controlling the timing of the operation of the strip engaging member 452. To this end each 80 fork member is provided at its end with a stop 470 which engages the flange 472 upon the adjacent cutter, as the cutters are separated after a fastening inserting operation to permit them to pass freely over the wire 85 during their upward movement, this stop being so proportioned and so located that it will remain in engagement with the flange 472 until the cutters start to close upon the strip to grip it for the succeeding fastening 90 inserting operation. This closing movement of the cutters, as more fully set forth in the Letters Patent above referred to, consists in an upward movement of the cutters toward a line through their pivots. The 95 upward movement of each cutter therefore lifts its flange 472 above the associated stop 470 and the controlling device 456 is thus permitted to move toward the cutters under the action of the spring 464. This movement of the controlling device toward the 100 cutters causes the strip engaging member 452 to move toward the strip and thus causes the V-shaped notch 454 to embrace the sides of the strip and to force the strip into the V- 105 shaped notch 455 in the plate 412. The strip engaging member 452 will at this time be in its lowermost position in the controlling device 456, the stem 458 being adapted to slide freely up and down in the bore in 110 the controlling device, and consequently said member will engage the strip at a point comparatively near the end of the strip. If, owing to the speed of the machine, the strip engaging member should not drop to its 115 lowermost position in the controlling device under the action of gravity, it will be forced to that position by the engagement of its upper end with the lower edge of the swinging frame 24 as the reciprocating head 40 reaches the upper limit of its movement. After the strip engaging member 452 has 120 engaged the strip, said member, together with the feed plate 412, moves downward with the cutters and with the reciprocating head 40 until said member engages a ledge 474 upon the guard plate or foot plate 351. The downward movement of the feed plate is stopped by its engagement with the work. After the strip engaging member has en- 130

gaged the ledge 474, the strip will move past said member during the continued insertion of the fastening, and the said member will maintain its engagement with that portion of the strip which is to form a fastening until the said portion is nearly inserted at which time the beveled face 476 upon each cutter will engage the adjacent correspondingly beveled contact surface 478 formed upon the member 452, there being one of these surfaces for each cutter, and the member will be forced away from the strip to permit the cutters to force the part which is to form the fastening down flush with the upper surface of the feed plate 412, as shown in Figs. 4 and 5 of the drawings. The member 452 is provided with a groove 480 which receives the tapered lower end of the presenter 117 when the head 40 comes into its lowermost position.

As hereinabove suggested, it is important, in a machine of this type, that the cutting edges of the cutters be exactly opposed at the time the fastening strip is gripped and also throughout the inserting movement. To this end each machine is supplied with means, not herein shown, for insuring an exact centering of the cutters when they are adjusted. It may happen, however, that with long usage some of the bearings associated with the cutters may become worn, so that there is a slight backlash in the movements of one or both of the cutters. It will be apparent that if there is any backlash in either or both of the cutters it may happen that the opening or the closing movements may not occur simultaneously, and that one may lag behind the other so that at the time the strip is gripped the cutting edges will not be exactly opposed. To avoid any possibility of such action of the cutters, the illustrated machine is shown as provided with means for insuring a simultaneous closing movement thereof so that the edges will be exactly opposed at the time the closing movement occurs. The illustrated means comprises a friction plug 482, mounted in a recess in the front plate 451, said plug being pressed into engagement with the adjacent cutter carrier by a spring disk 484. Opposed to the friction plug 482 is a hardened steel plug 486 to prevent wear of the opposite side of the head 40 by reason of the pressure of the plug 482 upon the cutter carrier. There is one of these plugs 482 for each cutter carrier and the action of the plugs is to retard the closing movement of the cutter carrier so that all backlash in the connections will be taken up before either cutter is brought into engagement with the strips, and the cutters will therefore be in their proper adjusted relation with their edges exactly opposed at the time the strip is gripped.

65. The operation of the machine with the va-

rious improvements embodied therein in accordance with the present invention will be clear, it is believed, from the foregoing description, but in order to set forth the improved operation in more precise form the various steps in the insertion of a single fastening will be briefly recapitulated: The machine being rendered operative to insert fastenings in the manner set forth in the Letters Patent, during the first downward movement of the cutters the awl 162 will be forced into the work by the engagement of one of the cutters therewith in the manner more fully set forth in said Letters Patent. The frame 24 will then swing toward the left in Fig. 1 to feed the work to bring the awl hole beneath the point at which the fastening is inserted, and as the head returns to its initial position the notch 455 in the feed plate 412 will be brought directly over said awl hole. As the frame is swung toward the left the head 40 starts to move upward and during the first part of its upward movement there is a relative movement of the slide 66 and the head 40, and the cutters are moved to open position so that they will pass freely over the strip W upon the continued upward movement of the head. During that part of the upward movement of the head which immediately succeeds the feeding of the work the feed plate 412 is also lifted high enough to bring it out of engagement with the previously partially inserted fastening, so that it will pass this fastening upon the return of the frame 24 to its initial position. The upward movement of the head also carries up with it the controlling device 456, the strip engaging member 452 moving relatively to said device during its upward movement until the upper end of the recess 462 engages the pivot pin 460. There will be a slight upward movement of the strip engaging member 452 with the controlling device 456 after the relative movement of these parts has taken place, so that said member will be a slight distance above the foot plate or guard plate 351 at the time when the cutters are actuated to grip the strip. In Fig. 2 the reciprocating head 40 is shown at its upper limit of movement at which time the upper end of the stem 458 of the strip engaging member 452 abuts against the under side of the front plate of the swinging frame 24, this relationship of these parts being provided to insure the movement of the strip engaging member to its lowermost position in the controlling device 456. During the first part of the downward movement of the head 40 there is no downward movement of the strip engaging edges of the cutters 46 and 48, a relative movement of the cutters and head 40 being thus caused which brings the said edges toward a line through the pivots of the cutter carriers and also brings the said edges toward each

other into engagement with the opposite sides of the strip W. As this movement of the cutters takes place, the flanges 472 upon said cutters move out of engagement with the stops 470 upon the controlling device 456, and said device is moved by its spring 464 toward the cutters, thus bringing the strip engaging member 452 into engagement with the strip, whereby the strip is confined between the V-shaped notch 454 in the member 452 and the V-shaped notch 455 in the feed plate 412, as shown in Figs. 3 and 6. As the cutters continue their downward movement, the strip engaging member 452 engages the ledge 474 upon the foot plate or guard plate 351 and the strip then moves past said member during the continued inserting operation, said member being forced away from the strip and out of the path of the cutters by the engagement of the beveled sides 476 of the cutters with the beveled contact surfaces 478 upon said member, as the cutters complete their inserting movement and sever the fastening from the strip. The stops 470 are again brought into retaining relation to the flanges 472 during the first part of the upward movement of the head 40 when the controlling device moves up with the head while a relative movement of the cutters to the head takes place, the cutters being held against upward movement to cause them to open in the manner hereinabove set forth.

It will be seen from the foregoing description that the strip is controlled and guided in a substantially positive manner from the time it is gripped until the inserting operation is substantially completed, and that this operation serves to insure the centering of the strip in the guiding opening in the feed plate 412, which opening is necessarily over the awl hole in the work. There is thus no opportunity for the strip to strike the work outside the awl hole or to enter the awl hole at an inclination thereto. When the insertion of fastenings is to be stopped, the awl is moved out of operative relation to the cutters, after it has brought the awl hole into operative position beneath the opening 455 in the feed plate 412. It will be apparent, however, that to complete the insertion of fastenings the work must be fed again to bring the partially inserted fastening beneath the solid portion of the plate 412. To this end the notch 455 in the feed plate 412 is made deep enough to insure the feeding of the work at this time. It will be observed, that the notch 455 opens toward the front of the machine and that, therefore, it offers no resistance to the turning of the work in feeding about a curve, this construction being especially useful when the machine is used for slugging heels. It will be noted also that the shapes of the notches 454 and 455 is so related to the direction

of the relative movement of the member 452 and the plate 412 that the strip guiding means exerts a strip centering action along two dimensions.

With fastening strips of other cross sections, notches of other shapes may obviously be provided, although it will be apparent that the V-shaped notches herein shown will be useful also with strips having different cross sections, as, for example, strips of circular cross section.

Having described my invention, what I claim as new and desire to secure by Letters Patent of the United States is:—

1. In a machine of the class described, means for gripping a fastening strip and inserting the end thereof into work, and means for guiding the end of the strip during the inserting operation comprising two members relatively movable into operative guiding relation to said strip, one of said members being provided with a strip guiding opening constantly in alignment with said strip.

2. In a machine of the class described, means for gripping a fastening strip and inserting the end thereof into work, means for guiding the end of the strip during the inserting operation comprising a member having a guiding opening constantly in alignment with said strip, and intermittently operated means for pressing the strip into engagement with the walls of said opening.

3. In a machine of the class described, means for gripping a fastening strip and inserting the end thereof into work, means for guiding the end of the strip during the inserting operation comprising a member having a guiding opening constantly in alignment with said strip and constructed to engage said strip at a plurality of points about its periphery, and means for temporarily pressing said strip into engagement with the walls of said opening at each inserting operation.

4. In a machine of the class described, means for gripping a fastening strip and inserting the end thereof into work, a guide for said strip having a strip guiding opening in fixed axial relation to said inserting means, and means for temporarily seating said strip in the opening in said guide at each inserting operation.

5. In a machine of the class described, means for gripping a fastening strip and inserting the end thereof into work, and means for guiding the end of said strip during the inserting operation comprising a strip engaging member having a guiding opening in fixed axial relation to the inserting means, and a member movable into and out of cooperative relation to said first mentioned member.

6. In a machine of the class described, means for gripping a fastening strip and inserting the end thereof into work, a com-

bined work feeding and strip guiding means, said means having a strip guiding opening into which the strip normally projects, and intermittently operated means for pressing said strip into engagement with the walls of said opening.

7. In a machine of the class described, means for gripping a fastening strip and inserting the end thereof into work, and means for guiding the end of said strip during the inserting operation comprising a member having a guiding opening constantly in axial alignment with the fastening strip and into which the strip normally projects and a second member likewise having a guiding opening, said second member being movable into and out of operative guiding relation to said strip.

8. In a machine of the class described, a single means for gripping a fastening strip, inserting the end thereof into work and severing a portion to form a fastening, and means operating to engage and guide the projecting end of said strip during the inserting operation, said means being movable with said inserting means during a part of its inserting movement and movable relatively to said means during the remainder of said inserting movement.

9. In a machine of the class described, means for gripping a fastening strip and inserting the end thereof into work, and a guide for said strip movable lengthwise of the strip into opposed relation thereto and movable transversely to the strip into engagement therewith.

10. In a machine of the class described, means for gripping a fastening strip and inserting the end thereof into work, and means for guiding the end of said strip during the inserting operation comprising members shaped to engage and guide opposite sides of the strip, said members being movable together lengthwise of the strip into opposed relation to said strip and being thereafter movable relatively to each other into guiding relation to said strip.

11. In a machine of the class described, means for gripping a fastening strip and inserting the end thereof into work, and means for guiding the strip end during the inserting operation movable lengthwise of said strip into opposed relation thereto before the strip is gripped and movable into engagement with the strip as said strip is gripped.

12. In a machine of the class described, means for gripping a fastening strip and inserting the end thereof into work, and means rendered operative by the gripping movement of said aforementioned means for guiding said strip end during the inserting operation.

13. In a machine of the class described, mechanism for gripping a fastening strip

and inserting the end thereof into work, and means for guiding the end of said strip during the inserting operation movable into and out of engagement with said strip and brought into operation by the gripping movement of said gripping mechanism.

14. In a machine of the class described, means for gripping a fastening strip and inserting the end thereof into work, and means rendered operative by the gripping movement of said aforementioned means for guiding said strip end during the inserting operation, said means comprising a member normally in guiding relation to strip and a member movable into and out of co-operative relation to said first mentioned member.

15. In a machine of the class described, reciprocating cutters arranged to grip a fastening strip, to insert the end thereof into work and then to sever the strip at the point where gripped to form a fastening, and means for guiding the end of said strip during the inserting operation controlled in its operation by the gripping and severing action of said cutters.

16. In a machine of the class described, a reciprocating head, means carried by said head for gripping a fastening strip and inserting the end thereof into work, and intermittently operated means also carried by said head and acting upon said strip across the line of the gripping movement of said gripping means for guiding the strip end during the inserting operation.

17. In a machine of the class described, a reciprocating head, means carried by said head for gripping a fastening strip and inserting the end thereof into work, and intermittently operated means for guiding the end of the strip during the inserting operation also carried by said head and acting upon said strip across the line of the gripping movement of said gripping means, said guiding means being movable relatively to said head along the strip.

18. In a machine of the class described, a reciprocating head, means carried by said head for gripping a fastening strip and inserting the end thereof into work, and intermittently operated means also carried by said head for guiding the strip end during the inserting operation, said means being constructed and arranged to exert a centering action upon said strip along two dimensions.

19. In a machine of the class described, a reciprocating head, means carried by said head for gripping a fastening strip and inserting the end thereof into work, and means for guiding the end of the strip during the inserting operation carried by said head and movable into and out of guiding relation to said strip.

20. In a machine of the class described,

a reciprocating head, means carried by said head for gripping a fastening strip and inserting the end thereof into work, and means for guiding the strip end during the inserting operation pivoted upon said head, yieldingly pressed toward said strip and controlled in its operation by said gripping means.

21. In a machine of the class described, a reciprocating head, means carried by said head for gripping a fastening strip and inserting the end thereof into work, means also carried by said head and movable into and out of engagement with said strip for guiding the end of the strip during the inserting operation, and means co-operating with said gripping means for controlling the operation of said guiding means.

22. In a machine of the class described, a reciprocating head, means carried by said head for gripping a fastening strip and inserting the end thereof into work, and means also carried by said head for guiding the end of the strip during the inserting operation comprising a member having a guide opening constantly in alinement with said strip, and intermittently operated means for pressing the strip into engagement with the wall of said opening.

23. In a machine of the class described, a reciprocating head, a pair of cutters pivoted upon said head and operating to grip a fastening strip and insert the end thereof into work, and a guide for guiding the end of said strip during the inserting operation also pivotally mounted upon said head.

24. In a machine of the class described, a reciprocating head, a pair of cutters pivoted upon said head and operating to grip a fastening strip and insert the end thereof into work, and means for guiding the strip end during the inserting operation pivoted upon said head to turn about an axis at right angles to the cutter axes.

25. In a machine of the class described, a reciprocating head, means carried by said head for gripping a fastening strip and inserting the end thereof into work, and means also carried by said head for guiding said strip end during the inserting operation, said means comprising a member pivoted upon said head and a member in fixed axial relation to said head.

26. In a machine of the class described, a reciprocating head, means carried by said head for gripping a fastening strip and inserting the end thereof into work, and means also carried by said head for guiding said strip end during the inserting operation, said means comprising a member pivoted upon said head and a member in fixed axial relation to said head, said members being movable together upon said head along the axis of said strip.

27. In a machine of the class described, a

reciprocating head, a pair of cutters carried by said head and arranged to grip an interposed strip of fastening material, insert the end thereof into work and then sever the strip at the point where gripped, and means for guiding said strip end during the inserting operation carried by said head and movable therewith along said strip and relatively thereto into engagement with said strip.

28. In a machine of the class described, means for gripping a fastening strip at a measured distance from its end, partially inserting that portion of the strip below the point where it is gripped and then severing the strip at said point to form a partially inserted fastening, means for feeding the work by engagement with the partially inserted fastening comprising a member having a guiding opening through which the strip passes during the inserting operation, and means for pressing the strip into engagement with the walls of said opening arranged to be moved out of operative position before the work feeding operation whereby the work may be turned freely about an axis outside of the strip.

29. In a machine of the class described, means for gripping a fastening strip, partially inserting the portion of the strip beyond the point where it is gripped and severing said portion from the strip to form a partially inserted fastening, means for feeding the work operated by engagement with the partially inserted fastening and comprising a member having a notch or groove through which the strip passes during the inserting operation, said notch or groove opening toward the front of the machine, and means for pressing the strip into engagement with the walls of said notch or groove to cause the fastening to be guided during the inserting operation arranged to be moved out of operative position before the work feeding operation whereby the work may be fed freely along a curved path having its center of curvature in front of the machine.

30. In a machine of the class described, means for gripping a fastening strip and inserting the end thereof into work, and means acting automatically to maintain a substantially constant frictional resistance to the gripping action of said gripping means to prevent lost motion due to wear or lack of proper adjustment.

31. In a machine of the class described, a pair of reciprocating cutters arranged to grip an interposed fastening strip, insert the end thereof into work and then sever said strip at the point where gripped, operating means for said cutters constructed to cause the cutters to be operated positively when performing each of the aforementioned steps, and spring operated means for

interposing a substantially constant frictional resistance to the operation of said cutters to prevent irregular operation such as may be caused by inertia or lost motion 5 as the parts become worn.

In testimony whereof I have signed my

name to this specification in the presence of two subscribing witnesses.

LOUIS A. CASGRAIN.

Witnesses:

H. DORSEY SPENCER,

ELMER B. GRUSH.

Correction in Letters Patent No. 1,115,504.

It is hereby certified that in Letters Patent No. 1,115,504, granted November 3, 1914, upon the application of Louis A. Casgrain, of Beverly, Massachusetts, for an improvement in "Machines for Inserting Fastenings," an error appears in the printed specification requiring correction as follows: Page 6, line 79, after the word "to" insert the word *said*; and that the said Letters Patent should be read with this correction therein that the same may conform to the record of the case in the Patent Office.

Signed and sealed this 2nd day of February, A. D., 1915.
[SEAL.]

R. F. WHITEHEAD,
Acting Commissioner of Patents.
